UNITED STATES PATENT OFFICE.

JOSEPH A. STEINMETZ, OF PHILADELPHIA, PENNSYLVANIA.

TORPEDO AND SUBMARINE GUARD.

1,219,879.

Specification of Letters Patent.

Patented Mar. 20, 1917.

Application filed October 23, 1915. Serial No. 57,514.

To all whom it may concern:

Be it known that I, JOSEPH A. STEINMETZ, a citizen of the United States, residing at Philadelphia, in the county of Philadelphia and State of Pennsylvania, have invented certain new and useful Improvements in Torpedo and Submarine Guards, of which the following is a specification, reference being had therein to the accompanying drawing.

For protecting vessels against submarine attacks it has been proposed to tow alongside the vessel a sheet adapted to explode any contact torpedo approaching laterally any vital part of the vessel, the sheet being supported wholly by float devices and usually at such distance from the vessel that it could not, practically, be sustained by arms therefrom.

According to the present invention, the protecting sheet is supported by boat, pontoon, or other suitable float devices and is arranged to swing laterally with respect to said devices so that rolling or rocking motion of the latter may produce no harmful strains, and the sheet is also provided, when desired, with a projecting point at the forward end of its lower margin, adapting it for destructive engagement with a submarine boat, this projection sometimes being the end portion of a very heavy bar.

In the accompanying diagrammatic drawings,

Figure 1 is a side view of a relatively small armed boat provided with a swinging keel sheet.

Fig. 2 is a like view showing a slightly different sheet.

Fig. 3 is a similar view showing a pontoon instead of a boat as a float device and a sheet of net-like construction.

Fig. 4 shows in plan a vessel protected by two sheet-supporting pontoons towed by a small boat.

Fig. 5 shows in like manner two long slightly divergent pontoons towed by the protected vessel itself but not supported thereby.

In Fig. 1, A represents a boat having a sheet B hinged to its bottom at C to swing laterally about an axis running along its keel line and provided with numerous perforations to facilitate its lateral movement in the water as well as to diminish its weight, and also provided with a beak or projection D at the forward end of its lower

side. The sheet may be of heavy sheet metal and may be as shown a rigid whole although it is not necessarily so, it being only necessary that it should prevent a torpedo from passing through it to a vessel to be protected by the sheet. Fig. 2 shows a sheet B' as imperforate and without the projection D. Fig. 3 shows a corresponding sheet as of heavy flexible net or link construction supported by a pontoon E instead of a boat and having at its lower margin a heavy bar F with a forwardly projecting end F'.

Usually, a vessel, as G, Fig. 4, will be protected by two sheets, one on each side, and when they are supported by pontoons or float devices without propelling power, as indicated at H, they may be towed by a small boat I through the use of towlines J. When no such small boat is used and when the float devices are not self-propelling, the latter may be towed by cables K from the protected vessel itself, the pontoons in this case preferably being slightly divergent toward the front so that they tend to remain at a distance from the vessel. The float devices may all be provided with one or more rudders or steering devices, indicated at L, and adapted to be set or controlled in well known ways to regulate the distance of the float from the vessel.

For illustration, the sheets are shown as supported by a single float device, but the number is not invariable.

Since the sheet extends downward in the water far enough to guard all vital parts and is also long enough, as a whole, to protect the central portion of a ship, it is of such weight that when moving rapidly the impact of the projection D against a submarine would probably disable the latter, whether the projection be a part of the sheet itself or be the projecting end of a very long and heavy bar. The devices are thus suited for guarding by attack as well as by their passive protecting function.

What I claim is:

1. In apparatus of the class described, the combination with suitable float devices, of an approximately vertical sheet supported by said devices, arranged to swing laterally with respect thereto and adapted to explode a contact torpedo approaching the vital parts of a vessel alongside said sheet, and means for advancing the sheet

1. Synchronously with and alongside a vessel to be protected.
2. In apparatus of the class described, the combination with suitable float devices, of a pendant sheet supported thereby, provided with numerous transverse openings and arranged to swing laterally with respect thereto, and means for advancing the sheet with and alongside a vessel to be protected and at a suitable distance therefrom.
3. In apparatus of the class described, the combination with float devices, of a heavy sheet supported thereby, adapted to explode contact torpedoes moving transversely toward any vital part of a vessel alongside the sheet and provided at its lower forward margin with a projecting submarine-engaging point.
4. In apparatus of the class described, the combination with float devices, of a laterally swinging sheet supported thereby and provided at its lower side with a heavy approximately horizontal bar for disabling submarines by impact.
5. In apparatus of the class described, the combination with two sets of widely separated approximately parallel float devices, of heavy pendant sheets supported wholly by the float devices, respectively, adapted to explode torpedoes moving transversely toward any vital portion of a vessel between said sheets, and arranged to swing laterally with respect to their float supports.

In testimony whereof I affix my signature.

JOSEPH A. STEINMETZ.
